CLAIM

The ornamental design for an ear tag applicator as shown and described.

DESCRIPTION

FIG. 1 is a right view of an ear tag applicator in a closed configuration.

FIG. 2 is a front view of the ear tag applicator in the closed configuration.

FIG. 3 is a top view of the ear tag applicator.

FIG. 4 is a front left upper isometric view of the ear tag applicator in the closed configuration.

FIG. 5 is a right view of the ear tag applicator in an open configuration.

FIG. 6 is a front view of the ear tag applicator in the open configuration.

FIG. 7 is a front left upper isometric view of the ear tag applicator in the open configuration.

FIG. 8 is a top view of an unloaded lower jaw of the ear tag applicator.

FIG. 9 is a top view of a loaded lower jaw of the ear tag applicator.

FIG. 10 is a front view of an unloaded lower jaw of the ear tag applicator.

FIG. 11 is a front view of a loaded lower jaw of the ear tag applicator.

FIG. 12 is a bottom view of an unloaded upper jaw of the ear tag applicator.

FIG. 13 is a bottom view of a loaded upper jaw of the ear tag applicator.

FIG. 14 is a front view of an unloaded upper jaw of the ear tag applicator; and,

FIG. 15 is a front view of a loaded upper jaw of the ear tag applicator.

Broken lines in a dash-dash pattern shown in the FIGURES depict boundary lines and additional features related to an ear tag configured to interface with the ear tag applicator. The broken lines shown in the FIGURES illustrate portions of the ear tag applicator that form no part of the claimed design.
